Primary Examiner — Jack Reickel*Assistant Examiner* — Melvin L Davis(74) *Attorney, Agent, or Firm* — Larson & Larson, P.A.; Justin P. Miller; Frank Liebenow(57) **CLAIM**

I claim the ornamental design for a water propulsion device, as shown and described.

DESCRIPTION

FIG. 1 is a front perspective view of a water propulsion device showing my new design;
 FIG. 2 is a top plan view thereof;
 FIG. 3 is a bottom plan view thereof;
 FIG. 4 is a left-side elevation view thereof, the right-side being a mirror image;
 FIG. 5 is a front elevation view thereof;
 FIG. 6 is a rear elevation thereof;
 FIG. 7 is a cross-sectional view thereof; and,
 FIG. 8 is a rear perspective view thereof.
